UNITED STATES PATENT OFFICE.

FRANK H. STANARD AND MAURICE L. STANARD, OF KANSAS CITY, MISSOURI.

OIL-BURNING APPARATUS.

Application filed June 9, 1922. Serial No. 567,144.

To all whom it may concern:

Be it known that we, FRANK H. STANARD and MAURICE L. STANARD, citizens of the United States, residing at Kansas City, in the county of Jackson and State of Missouri, have invented certain new and useful Improvements in Oil-Burning Apparatus, of which the following is a specification.

Our invention relates to oil burning apparatus and pertains more particularly to that type of apparatus in which a burner is employed in stoves and furnaces for utilizing oil such, for instance, as kerosene or distillate as a fuel instead of coal.

One object of the invention is the provision of mechanism for thoroughly breaking up the fuel oil into spray by means of air under pressure which combines with said spray and forms therewith an economical and highly combustible mixture which is carried by the force of the air to the burner where it is vaporized and consumed.

A further object is the provision of mechanism for automatically controlling the feeding of the oil and air forming the combustible mixture, said mechanism embodying a suitable thermostat which acts to stop the feeding mechanism when the temperature exceeds a predetermined degree and acts in starting said mechanism when the temperature falls below a certain degree, thus insuring a substantially, uniform temperature of any desired degree obtained by manually adjusting the thermostat accordingly.

A further object is the provision of mechanism for automatically shutting off the supply of fuel in the event that the flame at the burner should become extinguished and thus avoid the danger of flooding said burner and the stove or furnace with oil.

Other objects will hereinafter appear, and in order that the invention may be fully understood, reference will now be had to the accompanying drawings, in which:

Fig. 1 is a plan view of the apparatus with the burner installed in the fire-pot of a furnace.

Fig. 2 is an enlarged horizontal section on line II—II of Fig. 4, of a mixing tube and associated parts.

Fig. 3 is an enlarged detail of the thermostat.

Fig. 4 is a side elevation of the apparatus with the burner installed in the fire-pot of the furnace.

Fig. 5 is a vertical section of an oil container and a pump for raising the oil from said container, so that it may flow by gravity through a feed pipe to the mixing tube. 60

Fig. 6 is an enlarged broken sectional view of a portion of a trip mechanism for stopping the motor, which drives the oil pump and an air blower, in case the flame at the burner should become extinguished. 65

Fig. 7 is an enlarged longitudinal sectional view on line VII—VII of Fig. 2, of electrically controlled means for stopping the motor when the temperature in the apartment in which the thermostat is installed exceeds a predetermined degree. 70

Fig. 8 is a detail cross section on line VIII—VIII of Fig. 7.

Fig. 9 is an enlarged vertical sectional view of the burner. 75

Fig. 10 is a cross section of the burner on line X—X of Fig. 9.

Fig. 11 is a cross section of the burner on line XI—XI of Fig. 9.

Fig. 12 is a diagram of the electric circuits and mechanisms for automatically controlling the supply of oil and air to the mixing tube. 80

In carrying out the invention, we employ a liquid fuel container 2 of suitable capacity and having a removable lid 4 held in place by a tie-bolt 6. The lid 4 is equipped at its ends with handles 8 for convenience in moving the container 2 when desired. 85

10 designates a pump (Fig. 5), for lifting the oil from the container 2 so that said oil may flow by gravity to the mixing tube 12. Said pump 10, in the present instance, consists of a vertical casing 14 open at its ends and fixed to the lid 4 of the container 2, an endless cable 15 running around a drive sheave 18 in the upper portion of the casing 14, and a chamber 20 into which the oil is discharged as it is carried upwardly by said endless cable 15. The casing 14 has a hinged top 22, so that access may be had to the interior mechanism for inspection and repairs. The drive sheave 18 is fixedly-mounted upon a shaft 24 driven in the present instance by 100 an electric motor 26 (Fig. 1), mounted upon the container lid 4 beside the pump 10. 105

The oil discharged into the chamber 20 by the cable 15 flows by force of gravity into the mixing tube 12 through a feed pipe 28. The passage of the oil through the feed pipe 28 is manually controlled by means of 110

a valve 29 and automatically controlled by a self-closing needle valve 30 (Fig. 2), provided with a discharge nozzle 34 arranged axially within the mixing tube 12. The valve plug 36 of the needle valve 30 is urged towards its seat by a coil spring 38 and is automatically drawn away from its seat by a solenoid 40, the plunger 42 of which is connected to the valve stem 44 by a lever 46 fulcrumed at 48.

The mixing tube 12 is supplied with air from a blower 50 mounted upon the container lid 4 and driven by the motor shaft 24, Figs. 1 and 4. The opposite end of the mix-

ing tube 12 from that connected to the blower 50 terminates in a segmental vaporizer 52 surrounding the burner 54, which it enters and communicates with a mixing chamber 56 in the upper portion of said burner 54.

The burner 54, best shown by Figs. 9, 10 and 11, embodies the mixing chamber 56 which has slits or perforations 58 through which the vaporized mixture is discharged, a band 60 surmounted by the mixing chamber 56, an overflow chamber 62 surmounted by said vaporizing band 60, an air chamber 64 surrounding the overflow chamber 62, and an annular oil trough 66 surmounted by the air chamber 64 and provided with lugs 63 secured to the bottom of the overflow chamber 62 by screws 65. The segmental vaporizer 52 is provided at its inner periphery with a circular flange 68, which in case the flame becomes extinguished, directs the unconsumed oil into the interior of the burner 54 from which it is conducted from the overflow chamber 62 by a drain pipe 70 discharging into a trip cup 71 which causes the flow of the oil to the burner 54 to be automatically cut off as will hereinafter appear.

The annular oil trough 66 is supplied with oil through a feed pipe 72 leading from the container 2 and provided with a valve 53. The oil trough 66 is provided with a circular row of wicks 74 secured at their upper ends in bushings 76 fitting firmly within holes in the top wall of the trough 66, so that oil cannot overflow therefrom. The wicks 74 provide for a pilot light by drawing the oil upwardly through capillary attraction so that it can be ignited, combustion being supported by air admitted through the open bottom of the air chamber 64 and which passes through the perforations of two concentric bands 78, extending from the top of the oil trough 66 to the top of the air chamber 64 which has an annular opening 80 for the passage of the flame, so that such flame may impinge against the vaporizer tube 52 and the band 60 and thus vaporize the combustible mixture received from the mixing tube 12.

The thermostat 84 disclosed in detail by Fig. 3, which automatically regulates the supply of oil and air to the mixing tube 12

according to the temperature of the apartment in which it is installed by stopping and starting the motor 26 as will hereinafter appear, consists of a conductor 86 formed at its upper end into a spiral spring 88 fixed to a pin 90 projecting from a board or other support 92, which may be secured to a wall of the apartment. The lower end of the conductor 86 has a contact 94 adapted to engage either of the oppositely-disposed contacts 96, 98, adjustably mounted in the forked end of a lever 100, adapted to be secured at any point of its adjustment by a graduated segment 102.

Figs. 7 and 8 disclose a circuit breaker 104, which is mechanically controlled through the intermediacy of the trip cup 71 to cut out the motor 26 and prevent flooding of the burner in case the flame becomes extinguished, and is electrically controlled by the thermostat 84 to cut out the motor 26 in case the temperature in the apartment rises above a predetermined degree, or cut in said motor 26 should the temperature fall below a predetermined degree. The circuit breaker 104 is enclosed within a compartment 106 arranged on top of the oil container 2. Said circuit breaker 104 includes a cup of mercury 108, electrodes 110 and 112, levers 114 and 116 for lowering said electrodes 110 and 112, respectively, into the mercury 108 and raising them from said mercury, an insulated plunger 118 pivotally connected at one end of the lever 116, armatures 120, 122, spaced apart and fixed to said plunger 118, and a double-acting electromagnet 124 interposed between the armatures 120 and 122 and embodying supports 125 in which the plunger 118 is slidably mounted.

The electromagnet 124 embodies coils 126 and 128 would open cores 130, 131, respectively, and the adjacent ends of which are connected to a wire 136, connected to the secondary of a transformer 138 and leading to the conductor 86 of the thermostat 84. The opposite end of the coil 126 is connected to a wire 140 leading to the thermostatic contact 98, while the opposite end of the coil 128 is connected to the thermostatic contact 96 by a wire 142. The transformer 138 serves to reduce the voltage to the thermostat 84 considerably below the voltage in a motor circuit 160, so that there will be no danger of a person operating the lever 100 becoming injured in case of a short-circuit.

The lever 114 of the circuit breaker 104, is pivoted to one end of a connecting rod 144, which is pivoted at its opposite end to a crank 146 fixed upon one end of a rock shaft 148 journaled in bearings 149 fixed to the mixing tube 12. The other end of the rock shaft 148 is provided with a crank 150 pivotally connected to the upper end of a rod 152 connected at its lower end to the trip 71 through the intermediacy of a bail 154.

The rod 152 is protected by a tube 156 open at its ends and communicating at its lower portion with the drain pipe 70 to direct the overflow oil therefrom into said trip cup 71.

5 As shown by Fig. 12, the motor 26 is connected to the motor circuit 160, which is manually thrown in and out of circuit with supply mains 162 through the intermediary of a knife switch 164. The primary side of 10 the transformer 138 is connected across the motor circuit 160 by wires 166 and 168. The electrodes 110 and 112 are connected in series with the motor circuit 160, while the solenoid coil 40 is connected across the motor 15 circuit 160, by wires 170 and 172. A rheostat 114 is connected in series with the motor circuit 160 to regulate the speed of the motor 26.

The operation briefly stated is as follows: The switch 164 is closed and the contact 98 is manually swung into engagement with thermostatic contact 94. The rheostat 174 is then adjusted to obtain the desired motor speed. The circuit from the mains 25 162 enters the motor circuit 160 and energizes the transformer 138 which in turn energizes the local circuit including the wire 136, the thermostatic conductor 86, contacts 94 and 98, wire 140, and coil 126, causing 30 the latter to attract the armature 122 which results in immersing the electrode 112 in the mercury 108, the electrode 110 being normally immersed. The thermostatic lever 100 is then manually adjusted to move the contact 35 98 out of engagement with the contact 94, and is set at the proper point on the segment 102 to obtain the desired temperature. Should the temperature of the apartment rise above the degree for which the thermostatic 40 84 is set and cause the spring 88 to expand sufficiently to move the contact 94 into engagement with the contact 96, a circuit is established through the wire 136, thermostatic conductor 86, contacts 94 and 96, wire 45 142 and coil 128 causing the same to attract its armature 120 and raise the electrode 112 from the mercury 108. This interrupts the motor circuit 160 which remains open until the temperature falls sufficiently to cause 50 the spring 88 to contract and move the thermostatic contact 94 into engagement with the contact 98 and close the local circuit above-described, causing energization of the coil 126, which attracts its armature 122 and 55 closes the motor circuit 160 by lowering the electrode 112 into the mercury 108. Thus the motor 26 is automatically started and stopped according to the temperature in the apartment.

60 When the motor circuit 160 is closed by immersion of the electrode 112 in the mercury 108, the solenoid coil 40 is energized and effects the opening of the needle valve 30, so that the oil delivered to the pipe 38 by the pump 10 may flow into the dis-

charge nozzle 34 from which it is delivered to the mixing tube 12. The air blast caused by the blower 50 within the tube 12 impinges against the delivered oil with sufficient force to become thoroughly intermixed 70 therewith and break the oil up into a spray which is generated into a vapor in the vaporizer 52, before entering the mixing chamber 56 of the burner 54. As the highly heated vapor is forced from the mixing chamber 56 through the perforations 58 it is ignited by the pilot light embodying the wicks 74, said pilot light having been previously manually lighted to heat the vaporizer 52 and ignite the combustible mixture 80 as it is discharged from the burner 54.

Should the pilot light become extinguished from any cause while the apparatus is in operation, the oil in the combustible mixture will, of course, not become vaporized 85 and will flow into the trip cup 71, as hereinbefore mentioned, which will effect the opening of the circuit breaker 104 by raising the electrode 110 from the mercury 108. Opening of the circuit breaker 104 interrupts the motor circuit 160, thus stopping the motor 26, the pump 10 and the blower 50. Interruption of the motor circuit 160 also deenergizes the solenoid 40 allowing the needle valve 30 to close and shut off the flow 95 of any oil remaining in the pipe 28. The apparatus remains in this condition until again manually started.

From the foregoing description it will be understood that we have provided an apparatus embodying the advantages above pointed out and while we have shown and described the preferred construction, combination and arrangement of parts we reserve the right to make such changes as 100 properly fall within the spirit and scope of the appended claims.

Having thus described our invention, what we claim and desire to secure by Letters Patent, is:

1. In an apparatus of the character described a fuel oil container, a pump for lifting the oil from said container, a burner to which the oil is supplied, an electric motor for operating said pump, a circuit for said motor, a circuit breaker for interrupting said motor circuit, an overflow pipe leading from the burner, a cup to receive and be depressed by the overflow of oil discharged from said pipe, a rod from which said cup is suspended, a crank to which the upper end of said rod is connected, a rock-shaft upon which said crank is fixedly-mounted, another crank fixed upon said rock-shaft, and a connecting rod pivoted at one end to 115 the last-mentioned crank and pivoted at its opposite end to the circuit breaker to open the same when the cup is depressed.

2. In an apparatus of the character described a burner consisting of an overflow 120

chamber having an outlet at its lower portion, a mixing chamber surmounting said overflow chamber, and a vaporizer extending around the lower portion of said mixing chamber and having a flange leading into the overflow chamber.

3. In an apparatus of the character described a burner, an oil trough associated with said burner and having holes in its top portion, bushings fitting snugly within said holes, wicks fitting tightly into said

bushings and depending into the oil trough, an air chamber surmounting the oil trough and having an opening in its top wall, and two perforated bands spaced apart within the air chamber and extending upwardly from diametrically opposite points of the bushings.

In testimony whereof we affix our signatures.

FRANK H. STANARD.
MAURICE L. STANARD.
